ERASING SHIELD

Fred W. Radel, South Orange, N. J.

Application September 20, 1941, Serial No. 411,619

3 Claims. (Cl. 120—41)

The usual erasing shields for typewriters support the paper concentrically to the platen roller of the typewriter.

This is very unsatisfactory because thereby the contact pressure between the eraser and the thus formed sharply convex surface of the paper is extremely localized thereby causing an uneven erasing effect. Furthermore the convex form of the paper surface results not only in a perspective shortening, impairing somewhat the legibility in the process of correction, but also in a tendency of the paper and carbon paper to become dislodged and crumpled or even torn by such process, and frequently also in the necessity of moving the platen to effect complete erasure. The invention eliminates these disadvantages and speeds up the erasing operation by combining with the known concave platen engaging surface a less curved and preferably plane or substantially flat paper supporting surface.

In the drawing, the object of the invention is shown by way of example.

Fig. 1 is a plan view of the new shield;

Fig. 2 is a section on the line 2—2 of Fig. 1.

The new shield consists of the shield body proper *a* and the handle *b* directed at an angle thereto. Both may form together a unitary integral piece of suitable material such as plastic, metal, glass, fibre, etc.

The lower surface of the shield *a* has the known form of a concave surface *c* curved so as to fit around part of the surface of a platen roller.

In accordance with the invention the opposite or upper surface of the body *a* is not concentric to the surface *c*, but is a substantially flat, i. e. plane surface *d*. This plane surface supports the sheet to be corrected so that the erasing is done on a substantially flat and rigid surface which is much more practical and mechanically suitable than a curved surface.

For making possible the relative eccentricity of the surfaces *c* and *d* the upper and lower ends of the body *a* are thickened at *f* and *g* compared with the middle section *h*, the thickened part *f* having a somewhat rhomboidal cross-section.

The parts *b* and *f* meet in the edge *i*, and the parts *d* and *g* meet in the edge *m*. Both these edges may be conveniently rounded or blunted so that a blunt corner is formed in cross-section as shown in Fig. 2. The section *g* is relatively thin and preferably tapering or wedge shaped for close insertion between the papers and for convenience when placing the shield in position.

The modification shown and described above is preferred. However, for some special purposes the surface *d* may be not simply plane, but may be a flatly curved surface of a concavity opposite that of the surface *c* for exerting some guiding effect upon the eraser during erasing.

The modification shown and described is supposed to be made from rigid material.

If desired, however, the object of the invention 10 may be made of a flexible material like vulcanized rubber. In that event the cross-section, in a condition out of use, need not correspond to the form shown in Fig. 2, but in that out of use condition, the surface *c* for instance may 15 be straight and the surface *d* may be concave, provided the form is selected so that in use, when the surface *c* is conformed to the platen by the pressure, as explained, the surface *d* has the form shown in Fig. 2 or an analogous form, as 20 described.

Attention is called to the fact that, as may be seen from Fig. 2, obtuse angles are formed, in cross-section, at the edges *i* and *m*. In erasing the paper is bent around these edges by the 25 pressure of the fingers whereby the danger of dislodging or crumpling of the paper is eliminated. On the other hand by the obtuseness of said angles, and/or the bluntness of said edges respectively, the formation of objectionable permanent folding lines in the paper is avoided.

Of course, the provision of an angle or edge such as described at only one end of the surface *d* would suffice; preferably, however, both ends are shaped in this manner.

35 What I claim is:

1. An erasing shield comprising a dihedral body having a rear part with a concave seating surface adapted to encompass part of the platen roller of a typewriter and a front part with a 40 paper supporting surface of a considerably flatter curvature than said platen roller.

2. An erasing shield comprising a dihedral body having a rear part with a concave seating surface adapted to encompass part of the platen roller of a typewriter and a front part with a 45 substantially plane paper supporting surface.

3. An erasing shield, comprising, in combination, a body having a rear part with a concave seating surface adapted to encompass part of the platen roller of a typewriter and a front part with a 50 paper supporting surface of a considerably flatter curvature than said platen roller, and a wedge shaped part at one end of said body.
